ATTORNEY

UNITED STATES PATENT OFFICE.

STEPHEN J. QUALLS, OF CASPER, WYOMING.

PAN CLEANER.

Application filed April 4, 1925. Serial No. 20,797.

To all whom it may concern:

Be it known that I, STEPHEN J. QUALLS, a citizen of the United States, residing at Casper, in the county of Natrona and State 5 of Wyoming, have invented new and useful Improvements in Pan Cleaners, of which the following is a specification.

My present invention has reference to a means for cleaning ashes and cinders from 10 a stove or furnace of a character which will prevent all danger of fire from the removed ashes and which is also dust proof.

A further object is to provide a stove or furnace with an ash pan having a rounded 15 bottom portion terminating in an outwardly directed spout, and in which there is journaled a worm, the spout being normally closed by the ash door, while during the removal of the ashes and cinders I latch on 20 the spout a tubular member that also carries a worm to engage with the first mentioned worm and whose shaft is removably fixed to spiders carrying a closed reticulated drum arranged in a suitable closed casing, 25 both worm shafts being operated by a handle on the outer face of the casing, and whereby the ashes may be readily removed from the stove and deposited into the casing without dust or liability of fire, and 30 also wherein the cinders may be readily separated from the ashes during the removing process.

The drawing, which accompanies and forms part of this application, illustrates 35 the improvement.

In the drawing:—

Figure 1 is a side elevation of the improvement, with parts in section, a furnace being indicated by the dotted lines.

40 Figure 2 is a top plan view of the casing.

Figure 3 is a sectional view through the pan, approximately on the line 3—3 of Figure 1.

45 Figure 4 is a sectional end view of one of the spiral or worm shafts.

Figure 5 is a face view of the second shaft.

In the drawing a furnace 1 is indicated by the dotted lines in Figure 1. Fixed in 50 the furnace below the grate thereof there is a pan 2. The pan has its front wall and its sides inclined toward its bottom and its bottom is formed with a rounded concavity 3. At the inclined outer end 4 of the pan the concaved bottom is surrounded by a tubular pipe or stem 5. Journaled in suit-

able bearings in the bottom 3 of the pan 2 and also in its pipe extension 5 there are the ends of a worm carrying shaft 6. The outer end of the shaft 6 is formed with a 60 reduced squared extension 8 (Figure 5). The pipe extension is designed to be covered by the ash door of the furnace 1 when the latter is in closed position.

To remove the ashes from the pan, the 65 ash door of the furnace is opened, and there is arranged over the pipe 1 a pipe section 9 secured on one end of a substantially rectangular casing 10. The pipe section 9 has pivotally secured thereto oppositely disposed spring influenced latching members 11 that are designed to engage with an annular lug 12 on the pipe element 5. This effects a tight engagement between the pipe sections 9 and 5 and also holds the casing 75 10 properly positioned with respect to the furnace.

The pipe section 9 extends for a short distance into the casing 10 and also passes through one of the closed ends of a reticulated drum 13. The drum has the end 80 thereof through which the pipe 9 passes of a less diameter than the opposite closed end thereof whereby ashes and cinders will fall toward the said outer end of the drum. 85

Passing through a suitable bearing 14 in the outer end of the casing 10, and connected to spiders 15 that support the drum 13, there is a shaft 16. The shaft, at the portion thereof that passes through the 90 pipe section 9, is provided with a worm screw 17. The free end of the shaft 16 is formed with a socket 18 (Figure 4) designed to receive therein the squared extension 8 on the shaft 6. 95

A removable handle 19 has a socket engagement with the projecting end of the shaft 16 and the open top of the casing 10 is normally closed by a flanged cover 20. The frictional engagement between the 100 flange of the cover and the casing 10 will prevent passage of dust therethrough, the said cover being provided with a suitable handle whereby the same may be readily removed from the casing.

105 The turning of the handle will, of course, operate the screw conveyors so that the ashes and cinders will be drawn out of the pan into the reticulated drum 13 to separate unburned coal from the ashes and the ashes 110 will fall through the mesh of the said drum, the unburned coal being retained in the

drum. The casing and its pipe member 9 are disconnected from the pipe 5 by releasing the latch members 11, and the casing is moved to a suitable place to be emptied. 5 The crank 19 is removed from the shaft 16 and the screw conveyor 17, with its shaft 16, is drawn through the spout 9, which permits of the drum 13 being raised through the open top of the casing after the closure 10 for the said casing is removed, and the unburned coal in the drum will find an outlet through the opening in the end thereof that normally receives therethrough the inner end of the pipe extension 9. The improvement may be successfully operated 15 without the employment of the drum 13 as will, it is thought, be apparent.

Having described the invention, I claim:—

A furnace having a pan below the grate 20 thereof, said pan having a pipe extension at the bottom thereof, a spiral screw conveyor having its shaft journaled in the said

bottom and in the pipe extension of the pan, a normally closed casing, a reticulated drum therein, a pipe extension on one side of the 25 casing entering the drum and projecting outwardly from said casing, said pipe extension designed to receive therein the end of the first mentioned pipe, means latching the pipe sections so connected, a shaft passing centrally through the drum and through the pipe extension associated therewith, supporting means on the shaft for the drum, a spiral worm conveyor on the last mentioned shaft at the portion thereof received 30 in the pipe extension, interengaging means between the ends of both of the mentioned shafts, and an operating handle removably secured to the outer end of the last mentioned shaft. 40

In testimony whereof I affix my signature.

STEPHEN J. QUALLS.
